(57) **CLAIM**

The ornamental design for a lipstick container, as shown and described.

DESCRIPTION

The file of this patent contains at least one drawing executed in color. Copies of this patent with color drawings will be provided by the Office upon request and payment of the necessary fee.

FIG. 1 is a front, right perspective view from above of a lipstick container.

FIG. 2 is a front elevation view of a lipstick container of FIG. 1.

FIG. 3 is a rear elevation view of the lipstick container of FIG. 1.

FIG. 4 is a left side elevation view of the lipstick container of FIG. 1.

FIG. 5 is a right side elevation view of the lipstick container of FIG. 1.

FIG. 6 is a top plan view of the lipstick container of FIG. 1.

FIG. 7 is a bottom plan view of the lipstick container of FIG. 1; and,

FIG. 8 is a front view of the lipstick container of FIG. 1 with the lid removed and placed to the side.

The dash-dot-dash broken lines in FIG. 8 and the half-tone area within depict portions of the lipstick container that form no part of the claimed design.
